1,939,971

APPARATUS FOR DRY CLEANING

John Gans, Grymes Hill, Staten Island, N. Y., assignor to Columbia Appliance Corporation, New York, N. Y., a corporation of New York

Application March 31, 1931. Serial No. 526,651

4 Claims. (Cl. 68—38)

The present invention relates to an improvement in apparatus for dry cleaning, some features of which are more particularly applicable to the type wherein the cleaning liquid or solvent, after being used repeatedly or until it becomes dirty, is removed from the washer and cleansed or reclaimed, after which it is returned to the washer to be used again. This type of apparatus is distinguished from other types in which the 10 cleaning liquid circulates continuously through a filter or the like during washing and in such a way that the dislodged dirt is removed from the liquid in an operation continuous with the washing.

15 One object of the present invention has been to provide dry cleaning apparatus of the batch type, simultaneously utilizing two supplies of liquid, as distinguished from types utilizing a single supply, in which the dirty liquid is reclaimed 20 while the other or fresh supply is being used in the washer, the contemplated cycle including the following operations, namely, washing, removal of the used liquid, introduction of a fresh supply into the washer, and reclaiming the used liquid, as by distillation, while the washer operates 25 to clean a new batch of articles with the other supply. With two supplies of cleaning liquid in the system, it is apparent that my apparatus permits one to be in use for cleaning while the 30 other is being reclaimed and stored for use during the next cleaning operation.

I am aware that Hirst's United States Patent #1,697,766 discloses a washer, a used or dirty liquid receptacle, a still, and a clean liquid receptacle, so connected that the used liquid is fed 35 into the dirty liquid tank, from there to a still, and from the condenser of the still to a clean liquid tank. However, among many obvious differences in structure between Hirst's apparatus 40 and my improved device, said patentee does not disclose the mode of operation with two supplies of liquid which I have set forth above; but instead utilizes his washer as a dryer during reclaiming, so that, while the dirty liquid is being recovered, 45 the washer is used only to dry the last cleaned articles.

A further object of my invention has been to provide a liquid solvent dry cleaning apparatus 50 which may be located for use in an ordinary work room or other enclosed space without causing the air therein to be contaminated with volatilized solvent, and which, in normal use, permits the operator to perform his work effectively and quickly and with no discomfort due

to fumes liberated during the ordinary cleaning and drying operations.

To more fully secure the results last above mentioned, I enclose the washer in a cabinet or housing which is provided with means, as a blower or fan, for creating a condition of lowered pressure therein to produce a ventilating air current, thus entraining and controllably discharging both the fumes from the drying articles and the fumes, if any, from the washer, particularly when the latter is opened to receive or discharge articles.

The housing is preferably so related to the reclaiming apparatus that it also receives any uncondensed fumes or vapors passing over from the still or other volatile solvent reclaiming or purifying device which, in the illustrated embodiment, operates at atmospheric pressure, or open to the atmosphere or to the discharging effect of the blower at some convenient place, as within said housing or cabinet.

A further object of my invention has been to provide apparatus which affords all the advantages above suggested, among others, and which can be built at low cost and to occupy relatively little space, thus providing a system well adapted for a wide range of commercial requirements and not requiring unusually skilled operators. Furthermore, when used with non-explosive or non-combustible cleaning solvents, as for example, trichlorethylene, my improved apparatus presents many other advantages which will be readily apparent to persons skilled in the art.

A preferred embodiment of my invention is illustrated in the drawings accompanying the present specification and in which—

Figure 1 is a schematic front elevation, and

Figure 2, a central vertical section of a preferred form of still for use in my improved apparatus.

Referring to the drawings, apparatus embodying my invention is shown as including a cabinet 1, of suitable size and shape to house a washer 2 and garment or article supporting means such as a transverse rod 3, or the like, upon which garment hanger 4 may be suspended. Access may be had to the interior of the cabinet by providing removable panels as 5, or doors 6, or both. A condition of lowered pressure is induced inside the cabinet 1 by any suitable means such as a fan 7 actuated by a motor 8 or the like, said fan being arranged to exhaust the gaseous contents of the cabinet through an exhaust conduit 9.

The arrangement of the washer 2 within cabinet 1 and in relation to the doors 6 is such that, while engaged in duties connected with normal

100

105

110

use of the apparatus, the operator remains outside of the cabinet and readily performs his work from that position through the opening of one or both of the doors 6; and during such times air from the room or shop is drawn past him and into the cabinet from which it is discharged along with the fumes therein through exhaust conduit 9. Thus, with the use of my apparatus as above described, the business of dry cleaning can be advantageously conducted without subjecting operators engaged in the work to the disagreeable and at times injurious air conditions which prevail in dry cleaning establishments where the atmosphere is fouled by the fumes of the solvent or solvents employed in cleaning operations.

Associated in operative relation to the cabinet 1 is a tank having an upper compartment 10 and a lower compartment 11, said compartments being separated by a diaphragm or wall 12. The compartment 10 is intended to receive used or dirty liquid from the washer 2 and hold the same prior to its distillation or reclaiming in a suitable still or the like. A gauge 13 indicates the level of dirty liquid in the tank or compartment 10.

The compartment 11 is intended to receive and hold reclaimed liquid as it is recovered from a condenser forming part of a still, hereinafter to be described. A gauge 14 indicates the height or level of the liquid in the reclaimed liquid compartment 11.

One end of a main conduit 15 communicates with the interior of the washer 2. The other end of said conduit comprises two branches, one branch 16 leading to the dirty liquid tank or compartment 10, and the other branch 17 communicating with the reclaimed liquid compartment 11. A pump 18 is operatively interposed in the conduit 15, or at any other suitable or convenient place whereby it may serve to pump dirty liquid into the compartment 10 through the conduit 15 and the branch 16. A valve 19 in branch 16 prevents return of liquid through said branch into conduit 15 during inflow of reclaimed liquid from compartment 11, to be described.

The passage of reclaimed liquid through branch 17 is controlled by means of a valve 20. Thus, prior to the actuation of pump 18 for the purpose of moving the dirty liquid into the compartment 10, valve 20 is closed and valve 19 is opened. To avoid or prevent the flow of dirty liquid through branch 17 in case the operator should neglect to close valve 20, a check valve 21 is provided, said valve being adapted to close against pressure from pump 18 and to open when the reclaimed liquid is discharged from compartment 11 into the washer 2 by gravity.

The used or dirty liquid compartment 10 is connected by means of a pipe 22 with the boiler portion 23 of a still, the flow of liquid through said pipe 22 being controlled by valve 24. A steam coil 25 supplies heat to the interior of the boiler 23 and vapors generated therein are carried upwardly through a vapor conduit 26 into a condenser having a liquid discharge pipe 27 which conveys the distillate or reclaimed liquid into the compartment 11.

Any suitable type of still may be employed to recover or reclaim the dirty liquid. However, I prefer to utilize a form of still more particularly adapted to meet the needs of relatively small dry cleaning establishments and capable of rapidly volatilizing the liquid in the boiler portion 23 and rapidly condensing the vapor products thus

produced in a so-called atmospheric pressure device, or one in which the interior of the boiler and the condensing system attached thereto or communicating therewith operate at substantially atmospheric pressure. This type of apparatus obviously introduces a safety factor which is of material importance particularly when utilized in a dry cleaning system.

One form of condenser presenting the advantages above referred to is shown in greater detail in Figure 2. As indicated therein the condenser includes a water tank 28 to which water is supplied through a connection 29 in the bottom wall of said tank. A water discharge pipe 30, Figure 1, is connected to the upper portion of the tank 28 by means of a connection 31, Figure 2. The flow of water into tank 28 is regulated by hand operated valve 32. The upper end of vapor conduit 26 opens into a condenser chamber 33 within which a baffle 34 is suspended. Any distillate which results from condensation of the vapors on the walls of chamber 33 accumulates in the trough formed by the lower wall of chamber 33 around the upper end of conduit 26. A discharge pipe 35 communicates with the interior of said trough in chamber 33 to drain off the distillate as it accumulates therein. Uncondensed vapors rising from chamber 33 discharge into a similar chamber 36 having a similar trough and a drain pipe 37, and the uncondensed vapors from chamber 36 arise into chamber 38 which is also provided with a liquid collecting trough and a drain pipe 39. The drains 35, 37 and 39 are operatively connected with a discharge coil 49 which communicates with the discharge pipe 27 leading to the compartment 11.

In operation, as soon as the dirty liquid is discharged from compartment 10 into the boiler 23 steam is admitted into coil 25 causing vaporization of the liquid. The resulting vapors are condensed as above indicated and the reclaimed liquid is discharged into compartment 11. A suitably reduced temperature in the vicinity of the chambers 33, 36 and 38 and the pipes and coils associated therewith is effected by means of cold water circulating through the tank 28 in contact with said chambers and said pipes.

In connection with my improved still, I provide a pressure vent 41 communicating with the interior of the condenser chamber system above described, said vent being connected by means of a pipe 42 with the condensate return pipe 27 which discharges into clean liquid compartment 11. One purpose of this construction is to prevent the release and spreading of fumes in case some unusual condition exists in the still by reason of which, for example, violent vaporization takes place, or such that the contents of the still either condensed or uncondensed are forced into the vent 41 and discharged into the atmosphere of the room or shop in which the apparatus is employed unless they are otherwise disposed of. By connecting vent 41 with the discharge pipe 27, any excess liquid or uncondensed vapor discharging through the vent 41 from the condenser system is conducted through a relatively cool pipe 42 and into contact with relatively cool surfaces including that of such liquid as may be in the compartment 11. As a further safety feature, a vent pipe 43 has its receiving end opening into the interior of compartment 11 and its discharge end opening into the interior of cabinet 1. Thus, the condenser is vented to atmosphere through pipe 42, tank 11 and pipe 43. Moreover, by locating the discharge end of pipe 150

43 within the cabinet 1, I prevent the emission and spread of fumes in the room or work shop which accommodates the cleaning apparatus, and all fumes are drawn off by the ventilating 5 devices operatively associated with the cabinet 1 previously described.

From the foregoing description and the contemplated mode of operation indicated in connection therewith, it will be apparent that my 10 invention provides a dry cleaning apparatus or system which presents important features of novelty and utility. Among these, is the provision of a ventilated cabinet so arranged and constructed as to receive substantially all of the 15 fumes or vapors produced in connection with normal operation of the device. For example, where a volatile solvent is used, such as trichlorethylene, fumes thereof arise out of the washer 2 whenever the latter is opened either to 20 insert or to remove garments or other articles. Furthermore, the garments when removed contain a considerable amount of solvent, which evaporates in drying and ordinarily causes the greater part of the fumes produced in the dry 25 cleaning operation. However, in my improved apparatus the garments, immediately upon removal from the washer 2, are suspended or hung in extended condition within the cabinet 1. Another source of fumes is the vent or discharge 30 from the still particularly if it is open to atmosphere in the work room. As above indicated, any surplus vapors or fumes produced in the still of my apparatus are discharged through pipe 43 into the interior of cabinet 1. Thus, with the 35 ventilating system of said cabinet in operation the fumes are constantly being driven out through the conduit 9 and are being replaced by air drawn from the work shop or room in which the apparatus is located. The result is that my 40 improved dry cleaning system can be utilized in very small quarters and without injury or discomfort to the operators by reason of discharge of fumes into the room.

A further advantageous feature of my improved apparatus is the arrangement of the conduit connected to the washer in such a way that the same pipe accomplishes both the discharge of the dirty liquid and the feed in of the reclaimed liquid. This arrangement not only simplifies and 50 reduces the number of parts of the device but it also causes the regularly repeated automatic cleaning or flushing of the pump and the discharge conduit by the reclaimed liquid.

In case it is desired to operate the system with- 55 out a used liquid compartment or tank, a branch pipe 44 is interposed between the main conduit 15 and the boiler 23 and is provided with a control valve 45. Thus, by closing valves 19 and 24 and opening valve 45, the used or dirty liquid is 60 pumped directly to the boiler. As soon as the pumping operation is complete the valve 45 may be closed to prevent the return of liquid or vapors into conduit 15 except by way of the condenser system and the reclaimed liquid conduits previously described. However, if there is a supply 65 of clean liquid in tank 11 when pump 18 is stopped, and if valve 20 is open, clean liquid will flow through pipe 17, valve 20, check valve 21 and main conduit 15 into the washer; and in so doing 70 will prevent the escape of vapor arising in the still through pipe 44, even though valve 45 remains open.

Where the compartment 10 or equivalent tank is employed for receiving the dirty liquid from 75 the washer as a preliminary step to the reclaim-

ing operation, it is necessary to provide a vent for air forced out of said compartment 10 as the liquid is pumped in. One convenient means for accomplishing this result consists of a vent pipe 46 having its lower end opening through the diaphragm 12 and its open upper end extending into the dome of the compartment 10 above the level of liquid therein. This affords a passage for the discharge of air through said pipe 46 into the upper portion of compartment 11 and thence through pipe 43 into the cabinet 1. If desired, the same effect is secured by providing a pipe 47 extending through an upper portion of compartment 10 and connecting with pipe 43 outside of the tank. This mode of venting the air from the dirty fluid container is indicated in cases where the dirty fluid container is a separate unit from the clean fluid container or receptacle.

I claim as my invention:

1. Dry cleaning apparatus comprising a washer adapted to employ a volatile fume producing solvent as a dirt remover, a cabinet enclosing said washer, a still including a vaporizer and a condenser operatively connected to said washer and adapted to reclaim cleaning solvent after it has 100 been used in said washer, a conduit operatively connecting the washer and the still and adapted to convey said used solvent from the washer to the still, the interior of the condenser portion of said still being in free communication with the 105 interior of said cabinet to discharge therein uncondensed vapors of the reclaimed solvent, and a blower arranged and adapted to cause a condition of lowered pressure within the cabinet and to controllably discharge said vapors from the in- 110 terior thereof.

2. Dry cleaning apparatus comprising a washer adapted to employ a volatile fume producing solvent as a dirt remover, a cabinet enclosing said washer, a still including a vaporizer and a condenser operatively connected to said washer and adapted to reclaim cleaning solvent used in said washer, a conduit operatively connecting the washer and the still and adapted to convey used solvent from the washer to the still, a receptacle 120 operatively connected to the condenser portion of said still and adapted to receive reclaimed solvent therefrom, a conduit operatively connected with said receptacle and said washer and adapted to convey clean liquid from the receptacle to 125 the washer, the interior of said receptacle being in free vapor passing communication with the interior of said cabinet, and a blower arranged and adapted to cause a condition of lowered pressure within the cabinet and to controllably dis- 130 charge vapors from the interior thereof.

3. Dry cleaning apparatus comprising a washer adapted to employ a volatile fume producing solvent as a dirt remover, a still comprising a heater and a condenser for reclaiming solvent after use in the washer, a tank for dirty solvent operatively connected with said heater and with the washer, a tank for reclaimed solvent operatively connected to the condenser and to the washer, a cabinet enclosing said washer, conduit means for venting air and vaporized solvent from said dirty solvent tank into said cabinet, conduit means for venting air and vaporized solvent from said condenser into said cabinet, the latter being arranged and adapted to confine solvent fumes 140 liberated from the washer and vented from said tanks, and ventilating means for maintaining a condition of lowered pressure in the cabinet and for discharging said liberated and vented fumes 145 therefrom.

4. Apparatus for dry cleaning with a vaporizable solvent and for preventing the discharge of fumes therefrom into the atmosphere of a workroom in which the apparatus is located comprising a cabinet having an opening in a wall portion thereof and a removable cover for said opening, a washer for cleaning articles with solvent, means for supporting the cleaned articles in extended condition for drying, said washer and said supporting means being enclosed within said cabinet

and both so located in relation to said opening as to be readily accessible for effective manipulation by an operator reaching through said opening from a position in the workroom outside of said cabinet, and ventilating means for causing 80 a condition of lower pressure in the cabinet than in the workroom and for controllably discharging fumes from the cabinet.
